(57) CLAIM

The ornamental design for light masts for a trailer, as shown and described.

DESCRIPTION

FIG. 1 is a top perspective view of light masts for a trailer, according to a first embodiment;

FIG. 2 is a first side view thereof;

FIG. 3 is second side view thereof;

FIG. 4 is a front plan view thereof;

FIG. 5 is a rear plan view thereof;

FIG. 6 is a top plan view thereof; and,

FIG. 7 is a bottom plan view thereof.

The dashed broken lines in the figures illustrate the portions of the design that form no part of the claimed design.
